UNITED STATES PATENT OFFICE.

SAMUEL EDWARD DITTMAN, OF BROOKLYN, NEW YORK.

PROCESS OF CORRECTING PRINTING-PLATES.

1,370,418.

Specification of Letters Patent.

Patented Mar. 1, 1921.

Application filed August 20, 1919. Serial No. 318,720.

To all whom it may concern:

Be it known that I, SAMUEL E. DITTMAN, a citizen of the United States, residing at Brooklyn, in the county of Kings and State 5 of New York, have invented a certain new and useful Improvement in the Process of Correcting Printing-Plates, of which the following is a specification.

The invention relates to improvements in 10 the process or method of correcting printing plates.

Printing plates, as manufactured at the present time have considerable variation in 15 their height or thickness, as measured from the back or seat of the plate to the face or printing surface thereof. These defects are known to the trade as "shrinks or sinks" and these imperfect plates cause considerable loss of time in making ready a printing press 20 to print from the same as it seems to be commercially impossible to produce a level plate of uniform height by the usual methods because of the great care, time and skill required by the methods now in vogue, 25 and the fact that the usual shaving operation to which the plate is subjected after it is treated to level the printing face thereof, causes inaccuracies in the height of the plate.

30 The usual method or practice of utilizing these imperfect plates consists in providing the impression platen or cylinder of the printing press with a make-ready sheet upon which overlays or projections are built corresponding with the low portions of the plates and which serve to force the sheet to be printed into the low portions of the plates to secure a full impression. However, this forcing of the sheet out of its true 35 or ideal printing relation tends in many cases to impair the work. Also in long runs the make ready sheet becomes subject to a shifting action with respect to the impression platen and the printing plates owing to 40 its pliability or expansive qualities under varying atmospheric conditions, which not only impairs the printing but causes unequal wear on the plates.

It has also been the practice to place an 45 underlay sheet at the back of the plate upon which projections are built corresponding with the low portions of the plates to increase the thickness thereof at certain points, but this is unsatisfactory in that the plate 50 does not have a solid back or seat much less an even one whereby the plate rocks

and gives and interferes with the printing. Underlays are subject to the same shifting action as the overlays, and are equally unsatisfactory particularly where used to correct the inherent inequalities in the plate. 60

Where these imperfect plates are utilized by overlays and underlays the making ready of the plates is a long tedious operation requiring great skill and application. However, where the plates are of uniform thickness throughout and have a solid back or seat it is a relatively simple operation to make ready in that it is only necessary to overlay sufficiently to exert more pressure 70 on the heavily inked portions of the plates, such an overlay not being subject to the inherent disadvantages thereof to such an extent as to be unduly troublesome. 65

Other methods which have been proposed 75 for making ready these imperfect plates require great skill and application in the practice of the same and are subject to practical difficulties which are very hard to overcome.

80 The object of my invention resides in the provision of a method for accurately and preferably permanently correcting a plate so that it has an even printing face, a uniform thickness throughout and a solid back or seat, and which does not require great skill and application in the practice thereof.

The method is adapted to be practised independently of and prior to the use of the plates upon a printing press. 90

In describing the invention in detail, reference is had to the accompanying drawings, forming a part of this specification, and wherein like characters of reference are used to designate corresponding parts 95 throughout the several views, and in which:

Figure 1 is a partially sectional side elevation of a machine for testing the thickness of the printing plates to be corrected; Fig. 2, a sectional view of the same taken at 100 right angles to Fig. 1; Fig. 3, a partially sectional elevation of a machine for seating the plates; Fig. 4, a sectional view of the latter machine taken at right angles to Fig. 3; Fig. 5 is an enlarged bottom plan view 105 of the correction sheet hereinafter referred to; Fig. 6 is an enlarged exaggerated sectional elevation of a printing plate which has been corrected by the method of my invention; Figs. 7 and 8 are partial enlarged 110 sections of the testing machine in elevation similar to Fig. 1 showing the use of this

machine under certain circumstances hereinafter described; and Fig. 9 is a partial enlarged section of the seating machine in elevation similar to Fig. 3 showing the 5 use of this machine under certain circumstances hereinafter described.

In the drawings, numeral 1 designates the frame of the testing machine, including the base 2, which constitutes a lower pressure member, arranged to coact with the upper pressure member 3, slidably mounted in the frame, and actuated for vertical movement by the screw 4, threaded in the yoke of the frame, and provided with an operating 10 hand-wheel 5. At its lower end the screw is formed with an ordinary swivel 6, arranged to turn within a cap 7, fixed to the upper pressure member. The machine is constructed of metal throughout, the adjacent 15 inner faces of the pressure members constituting true unyielding surfaces, correspondingly shaped to suit the required form of the corrected printing-plates, indicated by the numeral 8. Fixed to the pressure face of 20 the upper pressure member 3 are a pair of bearer-bars 9, adapted to engage the opposite face of the lower pressure member 2, and to space the members apart under pressure a distance corresponding with the required 25 thickness of the plate. Clips 10, of any approved form, are provided for the lower member 2 for detachably holding the plate during test in a true position.

The initial step in the process consists in 30 taking a test of the plate 8 to be corrected to determine the variations in height of the printing plate. This is preferably accomplished by taking a correction or test sheet 11, preferably consisting of paper similar 35 to that commonly used for preparing the ordinary make ready. The plate 8 being inked in the usual manner, an impression is taken thereof upon the correction-sheet. This impression is preferably 40 taking in the testing machine as illustrated in Figs. 1 and 2, the plate 8 being adjusted upon the lower pressure member 2 face uppermost and the correction or test sheet 11 being laid thereon for receiving the impression, which is effected by impressing the 45 same upon the plate by means of the pressure member 3 actuated by the screw 4 and the bearer-bars serving to avoid excessive compressing or crushing of the plate. See Fig. 7. These faces being 50 true and unyielding surfaces unyieldingly impress the sheet upon the printing face of the plate and bring out an exact impression and clearly show the defects or variations in 55 the thickness of the plate by the comparative hardness of the impression upon the sheet. See Fig. 5 in which the unprinted portion 12 indicates the portion of the plate which is thinner than the heavily inked portion 13 60 of the correction-sheet. The aim in the

present case is to present the defects as exaggerated as possible in order that they may be the more readily observed and corrected. It will be clearly seen that this method of taking a test impression upon a sheet for 70 correction purposes is directly opposed to that carried out in the ordinary proof-press or printing-press wherein soft packing is used on the faces of the pressure members to cover up and hide the inequalities of the 75 plates.

In order to determine with great accuracy the nature of the low portions of the plate a number of test impressions are taken and sheets of different yielding qualities are 80 interposed between the true unyielding surface of the upper pressure member 3, adjacent the face of the plate, during the several impressions. See Fig. 7, in which only the correction or test sheet 11 is interposed, and 85 see Fig. 8 in which a test sheet 28 and a second sheet 29 is interposed between the surface of impression member 3 and the face of the plate, the test sheet 28 being next to the face of the plate. Due to the 90 fact that as the yielding quality of the pressure with which the test sheets are impressed upon the plate increases, the defects of the plate show less upon the correction-sheet and the true character and depth of the low 95 portions may be determined in this manner. Thus only the thinner portions of the low portions of the plate will show upon the test sheet 28 in Fig. 8, and the thicker portions of the lower portions will show on 100 the test sheet 11 in Fig. 7 in addition to the thinner portions. See Fig. 5 in which only the thinnest portion 30, inclosed within the dotted line, would be unprinted if the impression were made under the circumstances 105 shown in Fig. 8.

By the use of this method of testing the plate a very exact definition of the inaccuracies in the height of the plate may be obtained, thereby permitting a correction in 110 the first instance which corresponds very closely with the inaccuracies in the height of the plate, thus obviating the necessity of re-correcting the plate in practically all cases.

Then the indicated low portions of the 115 plate are built up by applying a suitable substance 14, see Fig. 6, to the back surface of the plate at the indicated low portions thereof to a thickness substantially corresponding with the relative difference in the thickness of the plate.

This is preferably accomplished by building up with a suitable substance the indicated low portions on the correction-sheet at the portions thereof corresponding with the 120 low portions of the plate on its upper or unprinted side to a thickness substantially corresponding with the relative difference in the thickness of the plate. In order that the low portions of the plate may be indicated 125

upon the unprinted side of the correction-sheet the unprinted side of the correction-sheet is pressed against a carbon sheet and the low portions outlined with a stylus on the printed side of the correction-sheet. The building up of the correction-sheet may be accomplished by the use of a variety of substances but preferably by the use of a substance having a plate engaging surface adapted to adhere to the plate during the embedding operation, hereinafter described, to effect the permanent embedding of the substance in the plate. A substance of this character which I have found to work very well where the heat is used during the embedding operation, as hereinafter described, is a mixture of black marine engine enamel and Portland cement, the proportion of cement being less than that of the enamel. Where necessary two or more coats of this mixture are applied each coat being dried (not baked) by the application of a low degree of heat before another coat is applied. Where necessary cement is sprinkled upon the wet mixture to obtain greater thickness and after this is dried a thin coat of enamel is applied to the sprinkled portions and dried to obtain perfect adhesion to the plate. The built-up correction-sheet is then transferred to the back of the plate and adjusted correspondingly opposite thereon (the high points of the sheet opposite the respective low points of the plate).

Then the substance as so applied is embedded in the back surface of the plate to form a plate having an even printing face, a uniform thickness throughout and a solid back or seat. Where, as is the case with the preferred substance hereinabove described, the substance has its plate engaging surface adapted to adhere to the plate it is permanently embedded in the back of the plate during the embedding operation with obvious advantages.

This embedding of the substance in the back of the plate is accomplished by subjecting the plate and substance, applied as above described, to pressure between parallel, true and unyielding surfaces with the face and back of the plate in controlled relation with respective surfaces whereby, if there be any inaccuracies between the thickness of the substance and amount that the plate should be built up the unyielding true pressure exerted will accommodate the same to accurately even the plate causing displacement in the effected portion of the plate or the building-up material or both depending upon the relative plasticity of the same. This embedding of the substance in the back of the plate is preferably accomplished by the use of the seating machine illustrated in Figs. 3, 4, and 9. Where this is used in the practice of the invention the plate is positioned in the seating machine with the

building up substance applied to the back thereof as above set forth, see Figs. 3 and 4 where the numeral 8^a designates the plate to be seated; 11^a, the built-up correction-sheet; 15, the frame; 16, the combined base and lower pressure member; 17, the upper pressure member, vertically movable in the frame and provided with a pressure screw and hand-wheel, similarly arranged as those described for the testing machine. In a like manner to the testing machine, the pressure members of the seating-machine have parallel, true and unyielding faces adapted to be spaced apart under pressure by the bearer-bars 18, fixed to the upper member 17. 80

In the embedding operation the plate is preferably heated to a somewhat plastic condition, about 450° F., when subjecting it to pressure to facilitate the embedding of the building-up substance into the back of the plate, and where the above described building-up substance is used to facilitate the adhesion of the same to the back of the plate. To effect this the pressure members of the seating machine are provided with heating chambers 19 and 20, in which are disposed gas burners 21 which are connected with gas pipes 22 and 23, leading from a convenient source of gas supply, the pipe 22 being flexible for the accommodation of the vertical movement of the pressure member 17 to which it is connected. The end walls of the chambers 19 and 20 are provided with apertures 24 through which the products of combustion may pass. In practice, see Fig. 9, an oiled sheet of hard paper 25 is interposed between the built-up correction-sheet and two news sheets 26 or other thin paper are placed between the oiled sheet and the lower pressure member 16 to provide a slightly yielding cushion to accommodate practical inaccuracies in the apparatus and method, and where the face of the plate is delicate and liable to be damaged by the required pressure two news sheets 27 or other thin paper are interposed between the upper pressure member 17 and the face of the plate to protect the face of the plate. The oiled sheet prevents the correction-sheet from sticking to it or the sheets 26 or the adjacent pressure member if these sheets are not used. 110 115 120

By reason of the fact that the plate and building-up substance are subject to pressure between parallel true and unyielding surfaces with the face and back of the plate in controlled relation with respect to said surfaces, the pressure exerted is intensified on the building-up substance, thus bringing the face of the plate to the proper level, if necessary, and embedding the building-up substance in the back of the plate. If after this is effected the thickness of the plate at the point where the building-up substance is embedded is thicker than the remainder of the plate, the pressure is still intensified 125 130

on the built-up portion and operates thereon to displace the effected portion of the body of the plate or the building-up substance or both, depending upon the relative plasticity of the same, so that the thickness of the built-up portion of the plate is reduced until the pressure is exerted throughout the plate, at which time the built-up portion of the plate is the same thickness as the remainder of the plate. Thus an automatic check is provided against overincreasing the thickness of the plate at the built-up portions thereof. The portion of the plate which is not built-up is effected in a similar manner where certain portions thereof are thinner than others, the pressure being intensified on the thicker portions thereof and displacing the same until the thicker portions are the same level as the thinner portions thereof. Because of this action I find that in the practice of the method in its preferred embodiment it is unnecessary to apply any building-up substance to such portions of the plate as are only slightly thinner.

I find that a pressure between 200 and 250 pounds per square inch of the plate is sufficient to effect the desired result where the above specified heat is used.

30 After the building-up substance 14 has been embedded in the back of the plate, as designated in Fig. 6, the correction-sheet may be removed by scraping it off preferably after first soaking the same with water.

35 After the removal of the correction-sheet the back of the plate may be painted with an aluminum paint to prevent the building-up substance from sticking when the plate is heated in other operations such as in bending a straight plate for a rotary printing press, as it is obvious that the present invention may be practised upon a straight plate as well as a curved plate.

By the practice of the present invention 45 in its preferred manner it will be noted that a permanently corrected plate of uniform thickness is produced having an even printing face and a solid back or seat, and that the method does not require great skill and 50 application to produce an accurately corrected plate and the method has an inherent corrective action which overcomes to a great extent inaccuracies in the plate not attempted to be corrected by the operative and 55 inaccuracies arising because of the operative in the practice of the method.

While I have shown and described the method of my invention as applied to a plate, the proper printing surface of which 60 should be disposed in one level, I contemplate the use of the invention as applying to a plate, the character of the printing surface of which requires that certain areas of the surface of the plate be elevated

from the level of other areas thereof, to 65 effect the leveling of the surface in each of such areas and the provision of a solid back or seat therefor, whereby the printing from each of such areas will be uniform and will require less printing pressure to effect a 70 uniform print from each of such areas than otherwise, this accurate leveling being practically impossible to obtain with sufficient accuracy by any of the methods, which have been heretofore proposed and practised, because they depend entirely upon the skill and application of the operative whereas the method of my invention of itself provides an automatic check on the amount that the low portions of a given area are raised 75 to prevent such low portions being thickened too much at the low portions thereof as hereinbefore set forth. Furthermore I contemplate the use of the invention before or after or at the time the areas of the surface 80 of the plate are raised, for reasons above set forth, but preferably after such raising of such areas is effected so that inaccuracies in the raising process may be corrected as well as other inaccuracies in the level of such 85 areas.

In carrying out the improved process, ordinarily, only a single operation, though the process may be repeated where necessary, is required.

95 What I claim as my invention and desire to secure by Letters Patent, is;

1. The process of correcting a printing plate consisting in taking a test of the plate to determine the variation in height of the 100 printing plate, building up the indicated low portions of the plate by applying a suitable substance to the back surface of the plate at the indicated low portions thereof to a thickness substantially corresponding with 105 the relative difference in the thickness of the plate and embedding the substance in said back surface of the plate as so applied by subjecting the plate and substance to pressure between parallel unyielding true surfaces with the face and back of the plate 110 in controlled relation with respect to these surfaces.

2. The process of correcting a printing plate consisting in taking a test of the plate 115 to determine the variation in height of the printing plate, building up the indicated low portions of the plate by applying a suitable substance to the back surface of the plate at the indicated low portions thereof 120 to a thickness substantially corresponding with the relative difference in the thickness of the plate and embedding the substance in said back surface of the plate as so applied by heating the plate to a plastic condition 125 and subjecting the plate and substance while the plate is in said plastic condition to pressure between parallel unyielding true sur-

faces with the face and back of the plate in controlled relation with respect to these surfaces.

3. The process of correcting a printing plate consisting in taking a test impression of the plate between unyielding true surfaces to determine the variation in height of the printing plate, building up the indicated low portions of the plate, by applying a suitable substance to the back surface of the plate at the indicated low portions thereof to a thickness substantially corresponding with the relative difference in the thickness of the plate and embedding the substance in said back surface of the plate as so applied by subjecting the plate and applied substance to pressure between parallel unyielding true surfaces with the face and back of the plate in controlled relation with respect to these surfaces.

4. The process of correcting a printing plate consisting in taking a test impression of the plate between unyielding true surfaces to determine the variation in height of the printing plate, building up the indicated low portions of the plate by applying a suitable substance to the back surface of the plate at the indicated low portions thereof to a thickness substantially corresponding with the relative difference in the thickness of the plate and embedding the substance in said back surface of the plate as so applied by heating the plate to a plastic condition and subjecting the plate and substance while the plate is in said plastic condition to pressure between parallel unyielding true surfaces with the face and back of the plate in controlled relation with respect to these surfaces.

40 5. The process of correcting a printing plate consisting in taking a test of the plate upon a correction-sheet to determine the variation in height of the printing plate, building up the indicated low portions on the correction-sheet at the portions thereof corresponding with the low portions of the plate to a thickness substantially corresponding with the relative difference in the thickness of the plate, transferring the built-up correction-sheet to the opposite side or back of the plate and embedding said built-up portion of the correction-sheet therein by applying pressure to the plate and built-up correction-sheet as so transferred to pressure between parallel unyielding surfaces with the face and back of the plate in controlled relation with respect to these surfaces.

60 6. The process of correcting a printing plate consisting in taking a test of the plate upon a correction-sheet to determine the variation in height of the printing-plate, building up the indicated low portions on the correction-sheet at the portions thereof corresponding with the low portions of the

plate to a thickness substantially corresponding with the relative difference in the thickness of the plate, transferring the built-up correction-sheet to the opposite side or back of the plate and embedding said built-up portion of the correction-sheet therein by heating the plate to a plastic condition and subjecting the plate and built-up correction-sheet as so transferred while the plate is in said plastic condition to pressure between parallel unyielding true surfaces with the face and back of the plate in controlled relation with respect to these surfaces.

7. The process of correcting printing plates consisting in taking a test of the plate upon a correction-sheet by means of pressure between unyielding true surfaces to determine the variation in height of the printing plate, building up the indicated low portions on the correction-sheet at the portions thereof corresponding with the low portions of the plate to a thickness substantially corresponding with the relative difference on the thickness of the plate, transferring the built-up correction-sheet to the opposite side or back of the plate and embedding said built-up portion of the correction -sheet therein by subjecting the plate and built-up correction-sheet as so transferred to pressure between parallel unyielding surfaces with the face and back of the plate in controlled relation with respect to these surfaces.

8. The process of correcting printing plates consisting in taking a test of the plate upon a correction-sheet by means of pressure between unyielding true surfaces to determine the variation in height of the printing plate, building up the indicated low portions on the correction-sheet at the portions thereof corresponding with the low portions of the plate to a thickness corresponding with the relative difference in the thickness of the plate, transferring the built-up correction-sheet to the opposite side or back of the plate and embedding said built-up portion of the correction-sheet therein by heating the plate to a plastic condition and subjecting the plate and built - up correction-sheet as so transferred while the plate is in said plastic condition to pressure between parallel unyielding true surfaces with the face and back of the plate in controlled relation with respect to these surfaces.

9. The process of correcting printing plates consisting in taking a test of the plate upon a correction - sheet to determine the variation in height of the printing plate, building up the indicated low portions of the correction-sheet at the portions thereof corresponding with the low portions of the plate to a thickness substantially corresponding with the relative difference in thickness of the plate, transferring the built-up correction-sheet to the opposite side

- or back of the plate, heating the plate to a plastic condition and embedding the built-up portion on the correction-sheet therein while the plate is in plastic condition by subjecting the plate and the built-up correction-sheet as so transferred to pressure between parallel unyielding true surfaces with the face and back of the plate in controlled relation with respect to these surfaces.
10. The process of correcting printing plates consisting in taking a test of the plate upon a correction-sheet by means of pressure between unyielding true surfaces to determine the variation in height of the printing plate, building up the indicated low portions on the correction-sheet at the portions thereof corresponding with the low portions of the plate to a thickness substantially corresponding with the relative difference in the thickness of the plate, transferring the built-up correction-sheet to the opposite side or back of the plate, heating the plate to a plastic condition and embedding the built-up portion on the correction-sheet therein while the plate is in said plastic condition by subjecting the plate and built-up correction-sheet as so transferred to pressure between parallel unyielding true surfaces with the face and back of the plate in controlled relation with respect to these surfaces.
11. The process of correcting a printing plate consisting in taking a test of the plate to determine the variation in height of the printing plate, building up the indicated low portions of the plate by applying a suitable substance having a surface adapted to adhere to the plate to the back surface of the plate at the indicated low portions thereof to a thickness substantially corresponding with the relative difference in the thickness of the plate and permanently embedding the substance in said back surface of the plate as so applied by subjecting the plate and substance to pressure between parallel unyielding true surfaces with the face and back of the plate in controlled relation with respect to said surfaces.
12. The process of correcting a printing plate consisting in taking a test of the plate to determine the variation in height of the printing plate, building up the indicated low portions of the plate by applying a suitable substance having a surface adapted to adhere to the plate to the back surface of the plate at the indicated low portions thereof to a thickness substantially corresponding with the relative difference in the thickness of the plate and permanently embedding the substance in said back surface of the plate as so applied by heating the plate to a plastic condition and subjecting the plate and substance while the plate is in said plastic condition to pressure between parallel unyielding true surfaces with the face and back of the plate in controlled relation with respect to said surfaces.
13. The process of correcting a printing plate consisting in taking a plurality of test impressions of the plate between true and unyielding surfaces and interposing sheets having different yielding qualities between the face of the plate and the adjacent surface during the several impressions, building up the indicated low portions of the plate by applying a suitable substance to the back surface of the plate at the indicated low portions thereof to a thickness substantially corresponding with the relative difference in the thickness of the plate and embedding the substance in said back surface of the plate as so applied by subjecting the plate and substance to pressure between parallel unyielding true surfaces with the face and back of the plate in controlled relation with respect to said surfaces.

In witness whereof I hereunto affix my signature this 19th day of August, 1919.

SAMUEL EDWARD DITTMAN.
